UNITED STATES PATENT OFFICE

AAGE GEORG PETER WIINGAARD, OF COPENHAGEN, DENMARK

SAVINGS BOX CLOCK

Application filed June 22, 1928, Serial No. 287,409, and in Germany June 29, 1927.

This invention relates to saving box clocks and, compared to the clocks known for the same purpose, the present invention has the following objects and offers the advantages 55 hereinafter referred to.

The arrangement allows of the use of coins of various sizes, without any change whatsoever, and merely by a simple manipulation, so that the manufacturer need only make one 10 standard size for the largest sized coin to be used in each single instance, all other sizes of coins being then unable to pass into the coin passage or falling through the same without affecting the clockwork.

15 The slot for inserting the coin is, according to the present invention arranged in the back wall of the clock and opens into the side of the coin passage, and not as heretofore into the upper end of the same.

20 Further, the object of the present invention is that the coin passage can be set by a simple manipulation both for a different thickness as also for a different diameter of coin.

25 The invention will now be described with reference to the accompanying drawings, in which:—

Figure 1 shows the movable and the fixed parts which effect the starting and stopping of the clock seen from the insertion side of the 30 clock.

Figure 2 shows the same parts seen from the left side in Figure 1.

Figure 3 shows the same parts seen from the right side.

35 Figure 4 shows the same parts seen from above.

Figure 5 shows a cross section along the line V—V in Figure 1.

40 Figure 6 shows a cross section along the line VI—VI in Figure 1.

In the drawings the clockwork itself is not shown as it does not form any essential part of the invention.

45 The numeral 1 designates a plate which carries the whole mechanism and the bent-over longitudinal side 2 of which forms the one fixed wall of the coin passage. To the wall 2 is fitted, pivoting on a pin 3, an unequal armed lever 4, 5. On the lever is also 50 fixed a pivot 6 which coacts with the one end

of another double armed lever 7, 8, the long free arm 8 of which can in known manner act on a wheel in the clockwork so that the lever 4, 5, when turned away from the position shown in Figure 2 turns the lever 8 from the position shown by full lines over into that shown by dot and dash lines in Figure 4. On the long arm 5 of the lever 4, 5 is fitted to a couple of ears 9 a plate 10, adjustable crosswise, having a bent-over edge 11 and forming the loose side of the coin passage, being parallel to the fixed plate 2. By the plate 10 not having holes for the screws but oblong slots, it is possible to adjust the plate 10, and at the same time the bent-over portion 11 to 60 a greater or smaller distance from the wall 2 according to the thickness of the coin to be used.

65 As a modification it may be mentioned that instead of shifting the plate 10 on the ear 9 of the lever 5 to set the distance between the fixed longitudinal side 2 and the adjustable side 11 of the coin passage, the same result may be obtained by letting the plate 10 be fixed on arm 4, 5 and making this arm itself 70 shiftable and adjustable on its pivoting axis 3.

75 To allow of adjusting the coin passage for different coin diameters the following arrangement is provided:—

80 The plate 10 limits the one narrow wall of the coin passage while the other narrow wall of the coing passage is formed by the bent-over edge 13 of a plate 14 screwed to the fixed wall 2, this plate 14 being so adjustable that the distance from plate 10 to the bent part 13 may be increased or reduced. Besides there is provided on the movable plate 11 a trip 85 85. Lastly there is a recess in plate 11, the purpose of which will hereinafter be explained.

87 On plate 1 there is towards the lower end a pivot 16 on which turns the toothed wheel 17 driven by the clockwork, while on the same 90 pivot or axis, and rigidly secured to said toothed wheel, is an exchangeable disc 19 having a recess 18. This disc 19 can co-operate with the bell crank 20, 21 and the latter is fitted on a pin 22 which is fitted movably 100

partly in a bearing in plate 1 and partly in a beam 23.

To the pin 22 is also fixed another double armed lever 24, 25, the one arm of which with its downward bent end projects into the said recess 15 in the movable wall of the coin passage 11 and serves to hold the coin held back while the other arm 25 with its likewise bent-over edge or the projection thereon 30 33, 26 swings in beneath the coin passage and so holds the operative coin. A spring 27 has the object of holding the arm 20 of the lever 21 up into co-operation with the disc 19.

This disc may be exchanged for other discs 15 with several recesses according to whether the savings box mechanism at certain periods shall have several paying-in terms.

The arrangement described operates in the following manner:

20 After the coin passage has by the adjustment of plate 10 on the ears 9 been set to the size (thickness) of a given coin and the plate 14 to the diameter of the respective coin, the arrangement is ready for use.

25 It is assumed that the parts have the position shown in Figure 1 and 2, the arm 8 being turned back, and in such position being in connection with a wheel in the clockwork and having made this to stop. Now a coin is inserted into the coin slit 28 between the outward-bent lip 29 of the fixed coin passage 2 and the corresponding lip 30 of the movable wall 11. On the coin entering the passage the lever 4, 5 is turned into the opposite position, the inserted coin in its fall pressing against the side of plate 10 turned towards the passage and thereby pressing the arm 5 outwards in the direction of the arrow *a* in Figure 2, whereby the pin 6 turns the arm 8 into

40 the opposite extreme position (indicated by the dot and dash lines in Figure 4). The clockwork is thereby released and will begin to go. The coin inserted cannot, however, pass through the coin passage but is held at its lower end by the trip 26 on arm 25. The clock will, as already stated, be going until it has turned the toothed wheel 17, and therewith the disc 19 so far that the recess 18 will be standing exactly opposite the arm 20, whereupon this arm, under the action of the spring 27 is drawn into the recess and thereby performs three operations:

45 1. The trip 26 is removed from the coin passage so that the coin resting on this trip can fall down into the coin box;

50 2. The trip 24 at the same time engages in the insecton 15 and prevents a possibly waiting coin from moving into the place of the operating coin and lastly

55 3. The lever 21 will settle behind the lug 37 and thereby prevent the lever 5 sliding back into its original position.

The clockwork will, in the meantime, continue to go and gradually the other edge of the recess 18 again releases the arm 21 of the

bell crank from the lug 37, and the lever 5 will now, possibly under action of the spring 31, go back into the position shown in Figure 1 so that the arm 8 will again stop the clock. When, however, before the clock is again stopped a new coin is inserted into the coin passage, this coin will, as long as the lever 20 is within the recess, 18, rest on the trip 24, but when thereupon the lever 20 is again pressed down and the trip is thereby again returned from the insecton 15 the coin will drop further until it comes to rest on the trip 26 and the clock is not stopped, by the lever 5 being unable to swing back, and the clock continues going.

Having now particularly described and ascertained the nature of my said invention and in what manner the same is to be performed, I declare that what I claim is:

1. A coin chute for a savings box clock 35 having a fixed longitudinal side wall, a movable longitudinal side wall parallelly adjustable relatively to said fixed wall, a movable narrow front wall integral with said movable side wall and a narrow rear wall adjustably secured to said fixed side wall.

2. A coin chute for a savings box clock having two parallel longitudinal side walls; one fixed and one movable, said latter presenting a bent over portion which forms the movable narrow front wall of the chute, means for adjusting the distance between said two side walls, a rear narrow wall formed by the bent over portion of a plate adjustably carried by said fixed side wall and means for adjusting the position of said rear narrow wall with respect to said front narrow wall.

In testimony whereof I affix my signature.

AAGE GEORG PETER WHNGAARD.
